OIL BURNER OF THE SPINNER TYPE

Kemper M. Hammell and Robert R. Witherell,
 Bloomington, Ill., assignors to Eureka Williams
 Corporation, Detroit, Mich., a corporation of
 Michigan

Application May 7, 1947, Serial No. 746,506

5 Claims. (Cl. 158—4)

1

This invention relates to oil burners and has particular relation to spinner type oil burners of relatively low fuel burning capacity.

Heretofore oil burners of the spinner type have been designed only to furnish heat for houses of relatively large sizes, this being the practice merely because such oil burners were comparatively complicated in design and large in size and consequently the expense involved in their construction was such that they could not be sold at a fairly low price. It was therefore necessary to design these oil burners in relatively large capacities because it was only where a burner of such size and capacity was required that such burners could be sold.

It is the purpose of this invention to simplify the design of such spinner type burners and to change the method of forming the inflammable mixture in such manner that the flame from the burner will be somewhat conical in formation and consequently can be used in a combustion chamber of considerably smaller size than heretofore has been required. With such types flame it will not be necessary to install metallic rings or other means around the outer wall of the combustion chamber for catching the particles of oil which may pass through the flame and be discharged radially outwardly therefrom. With the structure described these particles either will remain in the conically shaped combustible mass and will be burned along with other perhaps more finely atomized particles or they will be recirculated and atomized to a greater extent in the spinner head before being discharged into the combustible mass.

It is also the purpose of the invention to provide a new and improved spinner head for the burner in which the fuel will be completely atomized in the primary air of the burner prior to the delivery of any of the mixture to the region where it will be mixed with the main body of secondary air employed to support combustion of the burner flame. This feature employs a burner head which recirculates within the spinner head any particle of oil not sufficiently atomized to remain in suspension within the primary mixture prior to the entrainment of the latter within the secondary air stream.

Other and further objects of the invention will be apparent from the following specification taken in conjunction with the accompanying drawings of which there are three sheets and wherein:

Fig. 1 illustrates a vertical cross sectional view through an oil burner embracing the features of 55 the invention here disclosed;

2

Fig. 2 is a horizontal cross sectional view taken through the burner in two planes substantially along the line 2—2 in Fig. 1;

Fig. 3 is an enlarged fragmentary view of the 5 fuel metering pump disclosed in vertical section by Fig. 1;

Fig. 4 is a view similar to that shown by Fig. 3, except that Fig. 4 illustrates a modified form of fuel metering pump;

Fig. 5 is a fragmentary side elevational view of 10 the burner ignition device as the latter might be seen looking at the plane of line 5—5 in Fig. 1;

Fig. 6 is a diagrammatical illustration of the 15 oil burner illustrated by the preceding figures and of the electrical control system employed in its operation; and

Fig. 7 is a view similar to Fig. 6 except that Fig. 7 illustrates a modified form of control system for operating said burner.

20 Referring to Fig. 1, there is disclosed at the upper portion of the drawing a metallic support or combustion chamber wall 10 having a cylindrical opening formed therein by a laterally projecting annular flange 11. The support or wall 10 may form the lower wall of the combustion chamber in which the burner is employed, if desired.

Secured to the outer end portion of the flange 11 is a cylindrical flange portion 12 of a cylindrical casing 13 of the burner 15. Beneath the flange portion 12 the casing 13 is tapered inwardly as indicated at 14 to provide a region within the casing of expanding area.

35 Disposed within an intermediate portion of the casing 13 is a plurality of longitudinally disposed fins or supports 16, these being disposed in spaced relation circumferentially around the casing and projecting radially inwardly therefrom. Located internally with respect to these fins and secured

40 to and supported upon the inner extremities thereof is an electrical motor 17 comprising a motor casing 18, a stator 19 and a rotor 21. The rotor 21 is supported within the stator upon a centrally disposed shaft 22 which is mounted 45 for rotation within the motor casing 18 upon self-aligning bearings 23 and 24. The shaft 22 extends coaxially within the casing 13 a considerable distance beyond each of the ends of the motor 17.

50 Secured upon the end of the motor 17 remote from the wall 10 is a fuel metering pump 26 comprising a pair of oppositely disposed end blocks 27 and 28 each secured upon gaskets 29 against the opposite edges of cylinder block 31. The cylinder block 31 has a concentric opening formed therein in an enlarged portion at one end of which is

located an eccentrically disposed cylinder ring 33. Disposed in spaced relation internally of the cylinder ring 33 is a concentrically formed rotor 34 an end portion 36 of which is provided with a finished surface adapted operatively to engage and to provide a running fluid tight fit against the adjacent end of the end block 28. The rotor 34 has a threaded end 37 projecting therefrom which is secured within a threaded opening formed concentrically in the adjacent end of the shaft 22. A sealing ring 38 is disposed around the end of shaft 22 in such manner as to operatively engage the end block 27 to prevent leakage of fluid from the opening 32. Formed radially inwardly of the rotor 34 is a cylindrical opening or metering pump cylinder 39, the inner extremity of which is connected to a transversely disposed port 41 arranged within the rotor 34 remotely with respect to the center of rotation thereof.

Disposed within the cylinder 39 is a piston 42, the outer extremity of which is enlarged as is indicated at 45 to provide a portion having considerable mass, to be affected by centrifugal force resulting from the rotation of the rotor 34 to move the piston 42 inwardly and outwardly with respect to the cylinder 39 when the rotor 34 is rotated by the shaft 22. The enlarged end 45 of the piston 42 will be so held in engagement with the inner eccentrically disposed surface of the cylinder ring 33 that it will follow the surface of the ring for so actuating the piston.

The end block 26 is provided with two sets of ports indicated at 43 and 44, the port 43 being disposed in such position as to communicate with the port 41 during a portion of each revolution of the rotor 34 while the port 44 communicates with port 41 during a different portion of each revolution of the rotor 34. Port 43 also communicates with a fuel supply conduit indicated at 46, while 44 likewise communicates with an oil supply conduit 47 formed concentrically with respect to both the rotor 34 and the shaft 22.

It will be apparent that the rotation of the rotor 34 by the motor 17 will cause the pistons 42 to pump metered quantities of oil from the supply conduit 46 into the supply conduit 47.

The structure disclosed by Fig. 4 is similar to that disclosed by Fig. 3 except that in Fig. 4 the rotor 34 is permanently magnetized in the metallic portions thereof immediately adjacent the cylinder 39 and the port 41. Also a piston 242 is employed in the cylinder 39 which is likewise magnetized to provide a permanent magnet and the piston 242 further differs from the piston 42 in the respect that piston 242 is uniform in cross section from end to end.

It will be apparent that if the piston is polarized oppositely with respect to the adjacent portions of the rotor 34, the piston 242 will tend to be expelled from the cylinder 39 so that the outer end thereof will always tend to remain in sliding contact with the inner eccentric surface of the cylinder ring 33 during the rotational movement of the rotor 34.

At the end of the motor 18 opposite the metering pump 26 there is secured from the shaft 22 a fan 48, the angularly disposed blades or vanes 49 of which are arranged in such manner as to deliver an annular blast of air in a direction away from the motor 17. The air supplied to the fan 48 is drawn across the fins 16 extending around the motor 17 from the vicinity of the metering pump 26 where it is admitted to the casing through a plurality of spaced and circumferentially disposed air inlet openings 51. Operatively

associated with the openings 51 is a circumferentially disposed shutter 52 secured adjustably to the casing 13 by screws 53. The shutter is provided with openings equal in number to the openings 51 whereby variable quantities of air may be admitted to the casing 13 through openings 51 when the openings in the shutter 52 are variably positioned with respect to the openings 51.

Beyond the fan 48 and secured rigidly to the casing 13 at the periphery thereof is an air straightening baffle 54 having vanes 56 arranged oppositely with respect to the vanes 49 of the fan 48 in such manner as to receive the annular blast of air from the fan 48 between the vanes 56. The pitch of the vanes 56 is such as to neutralize the tendency of the annular blast of air to rotate in response to the operation of the fan 48. Beyond the baffle 54 and upon a central portion thereof inside the vanes 56 are secured a plurality of spaced supporting brackets 58 upon the upper ends of which is secured a stationary oil collecting and burner separating baffle 59. The baffle 59 has a flanged portion 61 disposed in spaced relation to the flange 12 of the casing 13 in such manner as to provide therebetween an annular discharge orifice 62 for supplying air to the burner combustion chamber from the blast delivered by the fan 48. Beneath the flange 61 the baffle 59 tapers inwardly as is indicated at 63 and 64 to provide with the wall 14 of the casing 13 an expanding channel 66 through which the blast of air from the fan 48 is delivered to the discharge orifice 62. The slope of each of the portions 63 and 64 of the baffle 59 is such that any oil not sufficiently vaporized or atomized upon reaching the flange 61 will flow downwardly upon the interior surface of the baffle toward the central portion thereof.

Immediately adjacent the central portion of the baffle 59 is a reversely projecting tapered flange 67 which with the portion 64 of the baffle provides a sump or depressed portion 68 in which unvaporized or unatomized oil flowing downwardly within the baffle will be collected. Secured upon the upper threaded end of the shaft 22 and projecting through opening 69 formed inside the flange 67 is a primary spinner 71 having a cylindrical passage 72 formed therein, the lower end of which communicates with the oil supply conduit 47 in the shaft 22. The upper end of the opening 72 communicates with the widely tapering opening 73 formed in the end surface of the primary spinner 71. Secured upon the opposite flanged end 74 of the primary spinner 71 is a secondary spinner 76, the inner portion 77 of which is tapered downwardly in spaced parallel relation to the portion 67 of the baffle 59.

Beyond the portion 77 the secondary spinner 76 comprises tapered portions 78 and 79, the slopes of which increase somewhat with respect to the slopes of the portions 64 and 63, respectively, of the baffle 69 in such manner as to provide an expanding tapering annular passage 81 between the secondary spinner 76 and the baffle 59. This passage leads from the sump or depression 68 in the baffle 69 toward the flange 61. The depressed portion of the spinner 76 between the portions 77 and 78 projects downwardly into the depressed portion of the baffle 59 between the portions 64 and 67 in such manner that any oil collecting within the sump 68 will be engaged by the depressed portion of the secondary spinner 76 and will be thrown outwardly in the direction of the flange 61 through the passage 81. Some of the air from the fan 48 will pass inwardly between

the supports 58, through opening 69 at the center of the baffle 59 and outwardly through the passage 81, there to come into contact with oil particles thrown outwardly by the depressed portion of the spinner 76. A further supply of air is added to the mixture so formed within the passage 81 by openings 82 formed through the baffle 59 in a region just outside of the supports 58. This supply of air will be received directly from the straightening baffle 56 and will be thrown outwardly in the passage 81 by the operation of the secondary spinner 76.

It will be noted that the outer edge of the secondary spinner 76 is somewhat outside of the outer edge of the primary spinner 71, yet inside the outer edge of the flange 61. Hence any finely divided particles of oil thrown by centrifugal force outwardly from the outer edge of the primary spinner 71 will strike the rotating outer edge of the secondary spinner 76, there to be more finely divided by the impact thereof upon the secondary spinner and due to the rotation of the secondary spinner will be thrown by centrifugal force radially outwardly therefrom toward the flange 61.

Disposed inside the flange 61 is an annular target ring 91 including an outer wall 94 and an inner tapering wall 95. The outer wall 94 is inside the outer edge of the flange 61, but beyond the outer edge of the secondary spinner 76. Due to such arrangement of walls it is apparent that any finely divided particles of oil which may be discharged from the edge of the secondary spinner 76 will engage the portion of the tapering wall 95 which is immediately adjacent the wall 94. As a result of such engagement, any of the particles which are finely enough atomized to support immediate and efficient combustion will be deflected outwardly from the wall 95 and will be entrained in the cone shaped blast of primary air from the passage 81 and from within the secondary spinner 76. Any oil so atomized will flow either inwardly upon the surface of the wall 95 or outwardly upon the surface of the wall 94.

In order to protect from excessive heat from the burner flame, the region inside the edge of the secondary spinner 76 so as to avoid carbonization of oil upon the surface thereof, there is disposed above the secondary spinner a circularly formed radiant heat baffle 83 which is secured in concentric relation to the secondary spinner 76 by a rotating stud 84. The stud 84 has a fluted end 86 secured within the cylindrical opening 72 in the primary spinner 71 for dividing the oil supplied by the supply conduit 47 to the cylindrical chamber into a plurality of parallel streams. Hence, it will be seen that the fluted portions of the stud 84 deliver relatively equal amounts of oil to all portions of the cone shaped end 73 of the primary spinner 71. The stud 84, being secured rigidly within the cylindrical opening 72, will rotate the radiant heat baffle 83 upon the secondary spinner 76.

The baffle 83, which consists of complementary spaced parts 87 and 88 secured together by rivets 89 terminates adjacent the outer periphery thereof in a region just inside the outer periphery of the secondary spinner 76.

In order to provide means for vaporizing some of the fuel for starting the oil burner there is provided inside the target ring 91 a preignition electrical heating coil 92 which is insulated from the target ring 91 and from other parts of the burner by electrical and heat insulating material

93. When electrical energy is supplied to the coil 92, as when starting the burner, it will be apparent that the unatomized oil previously referred to, which may flow inwardly and outwardly upon the walls 95 and 94 respectively, will be largely vaporized and therefore will render the primary mixture easily ignitable. After starting and during normal operation of the burner it is apparent that the unatomized oil which spreads out upon the surface of the walls 94 and 95 will be largely vaporized by the radiant heat from the burner flame. Any oil not so vaporized upon these surfaces will return by gravity to the sump 58 in the baffle 69.

15 In order to permit the return to the sump 68 of any particles of oil which may reach the flange 61 and which are not finely enough divided to be carried away by the flow of primary air through the burner, there is provided in the lower supporting edges of the target ring 91 a plurality of openings 96 through which such oil may flow downwardly upon the surface of the baffle 59.

20 In order that a sufficient amount of primary air may be supplied to the interior of the secondary spinner 76, there is also provided a series of spaced openings 98, these being formed circumferentially around the spinner adjacent the inner portion thereof.

25 In operation it will be apparent that any desired quantity of air may be admitted to the casing 13 through the openings 51 by varying the position of the circumferential shutter 52.

30 This air will be drawn across the outer surface of the motor 18 and will cool the motor due to the contact thereof with the fins 16. The air then will be discharged by the vanes 49 of the fan 48 in an annular blast upon the straightening vanes 56 which will thereupon deliver the blast of air against the outwardly sloping surface 64 35 of the baffle 59. Some of this air will move radially inwardly between the supporting baffles 58 and will pass through the opening 69 disposed centrally of the baffle 59.

35 Of the air which passes through the opening 69 some of this will pass outwardly between the adjacent surfaces of the secondary spinner 76 and the baffle 59 where reatomized oil thrown outwardly by the depressed portion of the secondary spinner 76 will be re-entrained in the air 40 delivered through the passage 81 to the vicinity of the target ring 91. The remainder of this air will pass through the openings 98 in the secondary spinner 76 where the fuel discharged from the edge of the primary spinner 86 will be 45 entrained therein both prior to and during the impingement of such fuel upon the edge of the secondary spinner 76.

45 Of the air which does not move radially inwardly from the region of the straightening vanes 56, some will pass through the openings 82 where it will be mixed with the oil and air moving between the adjacent surfaces of the secondary spinner 76 and the baffle 59 from the central region therebetween. The remainder, and by far the greater quantity of air delivered to the region beyond the straightening baffles 56, will move outwardly and forwardly through the expanding passage 66 and the discharge orifice 12. The secondary air so delivered from the orifice 12 will 50 be engaged by the primary air and fuel mixture delivered by the target ring 91, the general direction of most of which mixture is somewhat radially outwardly. The engagement beyond the burner of these two moving masses of fluid will 55 result in the development upon the burner of

an expanding annular cone shaped mixture of fuel and air which when ignited will burn in a similar formation.

The quantity and direction of the secondary air discharged beyond the discharge orifice 12 is such that when the fuel is properly atomized and vaporized inside the target ring 91, no particles of fuel will pass through the annular cone shaped column delivered by the orifice 12, and consequently it will be unnecessary to provide means inside the combustion chamber for atomizing, vaporizing or burning such fuel.

In order to ignite the combustible mixture so delivered by the burner there is provided at one side thereof an igniter 99 (see also Fig. 5) comprising a bracket 101 secured upon the side of the cylindrical portion 11 of the combustion chamber or burner supporting wall 10. This bracket is provided with two parallel portions 102 and 103 between the upper ends of which is pivotally supported upon rivets 104, an igniter element supporting bar 106. The bar 106 has projecting therethrough a pair of elongated terminals 107 and 108 between the outer ends of which is secured a hot-wire ignition device 109. The opposite ends of the terminals 107 and 108 beyond the support 106 terminate in contact elements 111 adapted to engage resilient contact members 112 secured to a lower portion of the bracket 101 upon terminals 113. Disposed between the elongated terminals 107 and 108 and secured at one end to a rigid portion of the bracket 101 is a bimetal thermostat 114, the movable end of which is secured to the pivotally mounted support 106.

The entire structure of the igniter 99 is located in such position that when the temperature of the thermostatic element 114 is not affected by the operation of the burner, the thermostat will be contacted in such manner as to position the hot air igniter element 109 in the path of the primary mixture emerging from the edge of the target ring 91. In such position the contacts 111 and 112 also will be closed so that an electrical current supplied to the igniter will flow through the device and will heat the hot wire element 109 to such an extent that it will ignite the mixture from the burner so delivered. However, after the mixture is so ignited and has burned for sufficient time to heat up all of the various elements of the burner and to produce a hot fire, the temperature of the thermostatic element 114 will be increased to such an extent as to expand the thermostatic element, thereby moving the end of the element attached to the support 106. The resultant movement of the support 106 will rotate the support 106 upon the rivets 104 to such an extent as to move the hot-wire element 109 outwardly to a position shown in dotted lines in Fig. 1 and indicated by the numeral 115. In this latter position the igniter will be out of the path of the primary mixture delivered by the burner and the flame resulting therefrom. During this same movement the contacts 111 will move away from the resiliently supported contacts 112 to such an extent as to break the electrical circuit through the hot-wire element 109.

In Figs. 6 and 7 there is disclosed two slightly different modifications of an electrical control mechanism for operating the burner.

In the modification shown in Fig. 6 the burner is indicated at 15, the preheating ring at 94 and the hot-wire igniter at 109.

The igniter 109 and the heater 94 are wired in series with a thermal safety switch 117 consist-

ing of a heating coil 118, a thermostatic electrical conductive element 119 and a reset button 121. Connected in series with the elements 92, 109 and 118 is another heater element 122 of a thermal timer switch 123, likewise having a thermostatic electrically conductive element 124. The thermostatic elements 117 and 124 are located adjacent the heaters 118 and 122, respectively, so that the thermostatic elements will be affected by the temperature of the heaters. The element 117 is so positioned that it will open the electrical circuit therethrough when the temperature of the heater 118 increases. The thermostatic element 124 is oppositely arranged with respect to the heater 122, that is, it is arranged to open the circuit therethrough when the temperature of the heater 122 increases. The elements 92, 109 and 118 combined have a relatively low resistance compared to the resistance of the heater 122.

The control mechanism disclosed by Fig. 6 also embraces a 3-way switch 126, a relay switch 127 for actuating 3-way switch 126 and a thermostat 128 for controlling the operation of the relay switch. The 3-way switch 126 consists of a pair of resilient contact bars 129 and 131, the bar 129 being adapted to engage terminal 132 to provide switch number 1—132— when moved in one direction and the bar 131 being adapted to engage terminals 133 and 134 to provide switches numbers 2 and 3 respectively when moved in opposite directions. The contact bar 131 normally is engaged with the terminal 134. The bars 129 and 131 are adapted to be so moved as to engage the terminals 132, 133 and 134, respectively, by actuating elements 136 and 137, respectively, the two latter elements being rigidly secured upon the end of an armature or core 138 operatively associated with the solenoid 139 of the relay 127. Actuating elements 136 and 137 are so arranged with respect to the bars 129 and 131, respectively, that the bar 131 will move out of contact with the terminal 134 and into engagement with the terminal 133 prior to the time when the actuating element 136 moves the bar 129 into contact with the terminal 132.

In Fig. 6 the high side of the line is indicated by the numeral 141, the low or ground side by the numeral 142, all of the elements previously described being wired as is indicated in Fig. 6.

The circuit disclosed by Fig. 6 is based upon the idea that the thermostat 114 for removing the igniter 109 from the burner flame can finally be used as a protective device to cause the control system to discontinue power to the motor 17 whenever faulty ignition may occur or when there is a flame failure due to the lack of oil or for any other reason.

It will be noted that one side of the thermostat 128 is connected to the high side of the line 141 by means of the circuit established through the solenoid coil 139 of the operating relay 127. The other side of the thermostat 128 is connected to the other side of the line 142 by means of the circuit established through switch 3, through the thermostatic element 119 of the thermal safety switch 117 and the elements 92, 109 and 118. Thus the operating relay 127 cannot be energized until the burner cools down sufficiently after a run to cause the contacts 111 and 112 of the igniter 99 to be closed. It will be noted that the circuit of the thermostat 128 can be completed back to the other side of the line 142 through the heater 122 of the thermal timer switch 123. The heater 122, however, has such a high resistance that it will limit the current flowing through the

solenoid 129 of the operating relay 127 to an insignificant amount. Thus the only way the relay 127 can be closed is when the contacts of the thermostat 128 are closed and the circuit through switch 127, the igniter 99 and the target ring heater 92 are closed.

When the proper conditions for starting are established, then a closure of the contacts of the thermostat 128 will cause the solenoid 139 of the relay 127 to be energized. This will cause the core 138 to be moved in such manner as to open switch 3 after switch 2 is closed, and thereafter further movement of the core closes switch 1. It will be noted that it is necessary to close the switches in this manner for the reason that switch 2 takes the thermal safety switch 117, igniter 99 and the target ring heater 92 out of the thermostat circuit and bridges the thermostat in series with the solenoid of the relay 127 across the power line. Immediately after closing switch 2 and the opening of switch 3, the circuit comprising the thermal safety switch 117, the igniter 99 and the target ring heater 92 to which the thermostat 128 was connected, is then connected directly to the high side of the line by the closing of the switch 1. The reason switch 3 has to be opened before switch 1 closes is that if the two switches were closed at the same time, there would be a direct short circuit from the high to the low side of the line through all of the switches.

Upon the operation of the relay 127, current can flow directly from the high side of the line into the igniter 99 and the electrically heated target ring heater 92 through heater 118 in thermal safety switch 117. Simultaneously the line voltage is put across heater 122 in thermo timer switch 123. The time of closing the switch resulting from the movement of thermostatic element 124 may be preadjusted to a time delay necessary to allow the igniter 99 and the target ring heater 92 to reach proper starting temperatures. When this happens the switch provided by thermostatic element 124 will be closed, causing the motor 17 to start the operation of the burner. Under these conditions oil and air will be properly mixed by the burner and will be ignited by the hot-wire 109 of the igniter 99. When the flame is established the heat of the flame will cause the thermostat 114 to move the hot-wire element 109 out of the flame and simultaneously open the contacts 111 and 112. If the flame is established within a predetermined time the current which has been flowing through the heater 118 of the thermal safety switch 117 will not have generated enough heat to cause the thermostatic element 119 of the switch to break the circuit therethrough and the burner will continue to operate under normal starting conditions.

However, under abnormal starting conditions when the flame is not established in a predetermined time after the beginning of the ignition cycle the heat generated in the heater 118 will be sufficient to cause opening of the switch provided by thermostatic element 119, thus shutting down the burner until this switch is closed manually by pressing the reset button 121. Under conditions of normal operation the thermostatic element 124 of the thermal timer switch 123 will remain closed all the time the thermostat 128 is calling for heat, due to the fact that the heater 122 thereof is bridged across the line by switch 1. When the contacts of the thermostat 128 open, the solenoid 129 of the relay 127 becomes de-energized, thus opening the switches 1 and 2, 75

closing switch 3, thus de-energizing the heater 122 of timer switch 123 and thus allowing the heater 122 to cool and to return to its normal starting condition. The heater 122 and the rate of heat absorption of the thermostatic element 124 can be so balanced to compensate for normal changes in line voltage, that is, when the line voltage is down it will require a longer time for the igniter 99 and target ring heater 92 to reach the proper operating temperatures. Under such conditions it will also require a longer time for the thermostatic element 124 to close its switch, thus starting the burner motor 17. Likewise, in cases of abnormally high voltage it will require less than average time for the igniter 99 and heater 92 to reach proper starting temperatures, in which case, due to the higher voltage across heater 122, the time delay will be reduced, thus starting the motor sooner.

In the structure disclosed by Fig. 7 there is shown a circuit that functions similarly to that shown by Fig. 6. However in this circuit the thermostat 128 is provided with a low voltage circuit due to the employment of a transformer 143, the primary and secondary coils of which are indicated at 144 and 146, respectively. The relay switch 127 and the 3-way switch 126 also are employed except that the relay 127 is connected to the rest of the control mechanism in a slightly different manner. The thermal safety switch 117 is the same type as that employed in Fig. 6, although the thermal timer switch 123 is a snap action type of switch mechanically coupled to the core 138 of relay 127 by a linkage indicated by dotted lines at 147 and pivoted at 148. When the solenoid 137 of the relay 127 is de-energized, its core drops to the unenergized position thereby transmitting motion through the linkage 147. This motion causes the thermostatically actuated element 124 of the switch 123 to be moved off of a magnet indicated at 149 and to return to the starting position. Also in Fig. 7 a light responsive contact switch 151 is employed instead of the thermostatically actuated element 114 employed in Fig. 6, and the target ring heater 92 is not employed in series with the igniter 99. Also the igniter employs a high tension spark device indicated at 152 instead of the hot wire element 109. This spark device is provided with high voltage current by a transformer 153, the secondary coil 154 of which is in circuit with the spark device 152, while the primary coil 156 thereof is connected through the control mechanism across the line.

For normal starting the furnace will be relatively cool and the light responsive switch 151 will be closed. When the contacts of the thermostat 128 close, as they will do when heat is required, a current will flow through the thermostat out to switch 151 in the burner, back through switch 1 to one side of the solenoid 139 of relay 127, through the solenoid 139, through the thermostatic element 119 of switch 117, back to the other side of the secondary winding 146 of the transformer 143. Current will simultaneously start flowing through the heater 118 which supplies sufficient heat to operate the thermostatic element 119 in a predetermined length of time. When the core 138 of the relay 127 is energized the switches 1 and 2 are closed and switch 1 is opened. Upon the closing of switch 2 the solenoid of relay 127 is no longer in series with the light responsive or fire-sensing switch 151 but is connected directly with the thermostat 128, so that switch 151 can open without causing the

core 138 in relay 127 to move outwardly of the solenoid 139.

The closing of switch 1 connects the common line and secondary terminal to the motor and to the ignition device 152. The return from the motor is to the high side of the line while the return from the ignition device is to the secondary winding 154 of the transformer 153. The closing of the ignition circuit causes the heater 122 to open the temperature operated switch element 124 within a predetermined time. When the element 124 does open the circuit therethrough, it is maintained in the open position by the magnet 149. Upon opening of this switch the heating element 118 will start to cool down, thus preparing itself for the next time the burner starts.

Under abnormal starting conditions when a flame is not established within the predetermined time allowed for this purpose, the fire-sensing switch 151 will not have opened and sufficient heat will not have been generated in the heater 118 to cause the element 119 to break the circuit therethrough and through the common circuit of the transformer secondary and the power line.

Where it is not desirable to use a common circuit for two voltages it is necessary to use a double pole switch in place of the switch 117 and another double pole switch instead of the single contact between terminal 132 and bar 129. Under such conditions it will be necessary to manually close the thermal safety switch 117 by pushing the reset button 121 which will reestablish normal circuit conditions. Under normal operating conditions when the circuit is open through thermostat 128 the core 138 becomes de-energized, thus closing the switch between terminal 34 and bar 134 and opening the other two switches of the switch structure 126. Thus the circuit is established for starting and when the fire-sensing switch 151 cools down sufficiently to close, the burner can be restarted upon the closing of the circuit through thermostat 138.

While we have illustrated and described preferred embodiments of our invention, it is understood that these are capable of modification, and we therefore do not wish to be limited to the precise details set forth, but desire to avail ourselves of such changes and alterations as fall within the purview of the following claims.

We claim:

1. An oil burner comprising a casing having a flange at one end providing an opening therein, a stationary baffle having a flange disposed in spaced relation to said casing flange, said flanges providing an annular opening therebetween for the discharge from said burner of an annular blast of secondary air, said baffle also being formed to provide an oil sump therein and an opening for the admission to the interior of said baffle of primary air for said burner, a fan for supplying to said openings said primary and said secondary air, an oil spinner located within said baffle flange, an oil metering pump for supplying burner fuel to said spinner, means for driving said spinner, said fan and said pump, and a target ring disposed within said baffle flange in position to be engaged by the oil from said spinner and in the path of the primary air from said baffle opening for forming within said annular blast of secondary air an outwardly moving mixture of atomized fuel and air, said spinner comprising a dished member arranged for rotation on a vertical axis and within and concentric relative to said target ring, said target ring being arranged to drain by gravity unatomized oil from

said target ring into said sump, said spinner being arranged to project into said sump for reatomizing the oil collected therein, said opening in said baffle being disposed radially inwardly of said sump whereby the air admitted by said opening will be thrown outwardly by said spinner for entraining therein the reatomized oil from said sump.

2. An oil burner comprising a casing having a flange at one end providing an opening therein, a stationary baffle having a flange disposed in spaced relation to said casing flange, said flanges providing an annular opening therebetween for the discharge from said burner of an annular blast of secondary air, said baffle also being formed to provide an oil sump therein and a plurality of openings for the admission to the interior of said baffle of primary air for said burner, a fan for supplying to said openings said primary and said secondary air, an oil spinner located on the downstream side of said baffle but within said baffle flange, an oil metering pump for supplying burner fuel to said spinner, means for driving said spinner, said fan and said pump, and a target ring disposed within said baffle flange in position to be engaged by the oil from said spinner and in the path of the primary air from said baffle openings for forming within said annular blast of secondary air an outwardly moving mixture of atomized fuel and air, said spinner comprising a dished member arranged for rotation on a vertical axis and within and concentric relative to said target ring, said target ring being arranged to drain by gravity unatomized oil from said target ring into said sump, said spinner being arranged to project into said sump for reatomizing the oil collected therein, said plurality of openings in said baffle being disposed radially both inwardly and outwardly of said sump whereby the air admitted by said opening will be thrown outwardly by said spinner for entraining therein the reatomized oil from said sump.

3. An oil burner comprising a casing having a flange at one end providing an opening therein, a stationary baffle having a flange disposed in spaced relation to said casing flange, said flanges providing an annular opening therebetween for the discharge from said burner of an annular blast of secondary air, said baffle also being formed to provide an opening for the admission thereto of primary air for said burner, a fan for supplying to said openings said primary and said secondary air, an oil spinner located within said baffle flange, means including an oil metering pump for supplying burner fuel to the upper side of said spinner, means for driving said spinner, said fan and said pump, and a target ring disposed within said baffle flange in position to be engaged by the oil from said spinner and in the path of the primary air from said baffle opening for forming within said annular blast of secondary air an outwardly moving mixture of atomized fuel and air, means for supplying unvaporized oil from said target ring to the underside of said spinner in order to permit the projection of such unvaporized oil thereby upon rotation thereof into engagement with said target ring, said spinner comprising a dished member arranged for rotation on a vertical axis and within and concentric relative to said target ring, said spinner also being provided with an opening for the admission therein of a portion of the primary air admitted by said baffle opening, whereby said primary air will be thrown

radially outwardly by centrifugal force on both sides of said spinner for mixture with the oil discharged by said spinner so as to form a primary mixture of atomized fuel and air for mixture with said annular blast of secondary air.

4. An oil burner comprising a casing having a flange at one end providing an opening therein, a stationary baffle having a flange disposed in spaced relation to said casing flange, said flanges providing an annular opening therebetween for the discharge from said burner of an annular blast of secondary air, said baffle also being formed to provide an opening for the admission thereto of primary air for said burner, a fan for supplying to said openings said primary and said secondary air, an oil spinner located within said baffle flange, means including an oil metering pump for supplying burner fuel to the upper side of said spinner, means for driving said spinner, said fan and said pump, and a target ring disposed within said baffle flange in position to be engaged by the oil from said spinner and in the path of the primary air from said baffle opening for forming within said annular blast of secondary air an outwardly moving mixture of atomized fuel and air, means for supplying unvaporized oil from said target ring to the underside of said spinner in order to permit the projection of such unvaporized oil thereby upon rotation thereof into engagement with said target ring, said spinner comprising a dished member arranged for rotation on a vertical axis and within and concentric relative to said target ring, said spinner also being provided with an opening for the admission therein of a portion of the primary air admitted by said baffle opening, whereby said primary air will be thrown radially outwardly by centrifugal force both within and without said spinner, and a radiant heat baffle disposed outwardly of said spinner for protecting the interior of said spinner from the radiant heat resulting from the operation of said burner.

5. An oil burner comprising a cylindrical casing and an electric motor, said casing being provided with a shaft disposed longitudinally thereof and driven by said motor, said shaft having an axially disposed oil supply conduit formed therein, a fuel metering pump mounted in said casing for operation by said shaft, said fuel metering pump being adapted to discharge metered quantities of oil through said conduit in said shaft for operating said oil burner, a fan mounted on said shaft adapted to induce a flow of air throughout said casing for operating said burner, said casing beyond said fan being provided with a stationary baffle having the outer portion thereof formed to provide an annular target ring, said target ring being spaced concentrically with respect to said casing to provide

an annular secondary air passage between said target ring and the adjacent end of said casing, a primary spinner disposed on the end of said shaft on the downstream side of said baffle and communicating with the conduit formed in said shaft for distributing the oil supplied by said conduit radially outwardly from said spinner, and a secondary spinner mounted on the end of said shaft for rotation therewith and with said primary spinner, said spinner comprising a dished member arranged for rotation on a vertical axis and within and concentric relative to said target ring, the periphery of said secondary spinner being disposed for receiving the oil discharged radially by said primary spinner, for atomizing a substantial portion of said oil and for discharging the unatomized portion of said oil from the outer edge thereof against said target ring, said stationary baffle being provided with a centrally disposed opening around said shaft for the admission of primary air to the space between said baffle and said secondary spinner, said baffle and secondary spinner also being provided with concentric depressed portions with the depressed portion of said spinner extending within the depressed portion of said baffle, said depressed portions in said baffles being adapted to collect unvaporized fuel from said target ring, said fuel when collected in sufficient quantity to be engaged by the depressed portion of said secondary spinner being thrown radially outwardly by said depressed portion of said secondary spinner and comingled and entrained within said primary air between said target ring and said secondary spinner, said mixture so formed being discharged axially outwardly of said burner from said target ring.
